UNITED STATES PATENT OFFICE.

MATHIAS F. BOHR, OF STICKNEY, SOUTH DAKOTA.

END-GATE LOCK.

1,399,842.

Specification of Letters Patent.

Patented Dec. 13, 1921.

Application filed April 15, 1921. Serial No. 461,592.

To all whom it may concern:

Be it known that I, MATHIAS F. BOHR, a citizen of the United States, residing at Stickney, in the county of Aurora, State of 5 South Dakota, have invented certain new and useful Improvements in End-Gate Locks; and I do hereby declare the following to be a full, clear, and exact description of the invention, such as will enable others 10 skilled in the art to which it appertains to make and use the same.

This invention relates to new and useful improvements in locks and particularly to locks for wagon end gates.

15 One object of the invention is to provide a lock or latch for an end gate which is used in connection with the type of gate which is formed in two hinged sections, one of which carries a bifurcated member extending trans- 20 versely of the other section, and in which bifurcation the lock is received, means being carried by the lock for releasable engagement with the bifurcated member to prevent accidental displacement of the lock.

25 Other objects and advantages will be apparent from the following description when taken in connection with the accompanying drawing.

In the drawing:

30 Figure 1 is an elevation of an end gate showing the invention applied thereto and in operative position.

Fig. 2 is an enlarged sectional detail view 35 through the locking device and portion of the end gate.

Referring particularly to the accompanying drawing there is shown an end gate which includes the two sections 10 and 11, hinged together at 12, the section 10 having 40 thereon the member 13 which extends longitudinally of the outer face of the section 11. The free end of this member 13 is formed with a bifurcation 14, and secured to the outer face of said end, and extending around 45 the bifurcation, is a flat metal wear plate 15. In one portion of the plate 15, at one side of the bifurcation, and also in the portion of the member 13, therebeneath, is an opening 16.

50 Disposed through the section 11, is a bolt 17, and mounted on the outer end of the bolt is a transverse head 18 in the form of a channel. On the inner end of the bolt, at the other side of the section, is a nut 19. Dis- 55 posed within the channelled head is the inner angular portion 20 of the handle 21, a pivot pin 22 being disposed through the por-

tion 20 and the side walls of the head. On the end of the portion 20, remote from the handle 21, is an angularly extending nose 23 which is arranged to enter the opening 16, when the head is swung into position transversely of the bifurcation, as clearly shown in the drawing. Between the bottom wall of the channelled head and the inner face of the member 20, is disposed a leaf spring 24 which normally exerts pressure to urge the nose into the opening 16. Thus, when the head is disposed transversely of the bifurcation, and rests on the wear plate 15, with the nose 23 properly seated in the opening 16, the bolt, which carries these parts, cannot be accidentally rotated. When, however, it is desired to remove the gate, the operator presses the handle inwardly toward the gate, 70 which rocks the member 20 on its pivot and releases the nose 23 from the opening 16, thus permitting the rotation of the head into a position longitudinally of the bifurcation. The bifurcated member can then be moved, 75 together with the section 10 of the gate, outwardly, so that the gate may be readily removed from the wagon.

When the gate has been properly placed 80 between the cleats of the wagon, and the head 85 disposed through the bifurcation, the operator presses the handle inwardly so that the nose 23 will escape the end of the member 13, and be placed on the outer face of the wear plate 15. Upon rotating the head, by 90 means of the handle, into a position transversely of the bifurcation, the spring 24 will cause the rocking of the member 20 and snapping of the nose 23 into the opening 16.

95 What is claimed is:

The combination with a wagon end gate having a pair of hinged sections and one of them having a bifurcated member extending longitudinally on the outer face of the other section, and a wear plate on the bifurcated member adjacent the bifurcation, of a bolt rotatably supported in the said other section and having a transverse channelled head for movement through the bifurcation, and a spring pressed handle mounted pivotally in 100 the head and having a nose for engagement in an opening of said plate when the head is disposed transversely of the bifurcation.

In testimony whereof, I affix my signature, in the presence of two witnesses.

MATHIAS F. BOHR.
